CLAIM

We claim the ornamental design for the pipe-to-pipe connection, as shown.

DESCRIPTION

FIG. 1 is a front side perspective view of a pipe-to-pipe connection in an assembled configuration showing the design;

FIG. 2 is a rear side perspective view showing the design in FIG. 1;

FIG. 3 is a front elevational view thereof;

FIG. 4 is a rear elevational view thereof;

FIG. 5 is a first side view thereof;

FIG. 6 is a second side view thereof;

FIG. 7 is a top plan view thereof;

FIG. 8 is a bottom plan view thereof;

FIG. 9 is an assembled view of the pipe-to-pipe connection in its environment connecting a pipe to a pipe with fastening elements inserted in the holes; and,

FIG. 10 is an exploded view of the pipe-to-pipe connection in its environment.

The broken lines show environmental structure of the pipe-to-pipe connection that form no part of the claimed design.
